UNITED STATES PATENT OFFICE.

RALPH H. UPSON, OF AKRON, OHIO, ASSIGNOR TO THE GOODYEAR TIRE & RUBBER COMPANY, OF AKRON, OHIO, A CORPORATION OF OHIO.

RANGE-FINDING INSTRUMENT.

1,317,670.

Specification of Letters Patent. Patented Sept. 30, 1919.

Application filed November 9, 1916. Serial No. 130,878.

To all whom it may concern:

Be it known that I, RALPH H. UPSON, a citizen of the United States, residing at Akron, in the county of Summit and State 5 of Ohio, have invented new and useful Improvements in Range-Finding Instruments, of which the following is a specification.

My present invention relates to position finders for use in connection with a military captive balloon, in order that the observations of the balloon may be corrected to compensate for the alterations in the balloon's height and drift, with respect to a fixed position on the ground.

15 The observation balloon has come to be a recognized necessity in modern warfare, and particularly as a range finder, wherewith the fire of long distance batteries may be directed. When a captive balloon is sent up, 20 however, to report angles and ranges of the enemy's fixed batteries or trenches, it will be apparent that some correction must be arranged for this data in order to compensate for variations in elevations of the balloon and for its constantly shifting position in the air with respect to its tethering point upon the ground.

It is to accomplish these corrections for the height and drift of the observational 30 balloon, with respect to the ranges or other data gathered by the observers in the balloon, that I have devised my present apparatus, and it has been one of the principal objects of my invention to provide means of 35 a mechanical nature which will be adjustable to follow the irregular movements of the balloon, and which, when so adjusted, will automatically record the balloon's position with respect to any fixed point upon the 40 ground, so that the desired corrections in the observer's data may be immediately made.

The above and additional objects of a similar nature, which will be hereinafter more specifically treated, are preferably accomplished by such means as are illustrated 45 in the accompanying drawings, described in the following specification, and then more particularly pointed out in the claims which are appended hereto and form a part of this 50 application.

With reference to the drawings, wherein there has been illustrated a preferred embodiment of the invention as it is reduced to practice and throughout the several views

of which similar reference numbers designate corresponding parts;

Figure 1 is a panoramic view illustrating the corrective sight of this invention in actual use;

Fig. 2 is a cross-sectional view taken longitudinally through the principal elements of this invention;

Fig. 3 is a plan view of the same subject matter;

Fig. 4 is a perspective detail of the vertical arm of the sight;

Fig. 5 is a partial perspective of the horizontal arm of the sight; and

Figs. 6 and 7 are diagrammatic illustrations of the theories of use of the instrument.

The data gathered by an observational balloon in the effort to locate a distant point with relation to the balloon falls naturally under two heads, namely; the distance from 75 the balloon to the point; and the angle which a line connecting the balloon with the point makes with some fixed base line, such as a north and south line. In order that the distant point may be related to some point upon 80 the ground adjacent the balloon it is only necessary to know the angle which a line (projected on the ground) connecting the balloon with the ground point makes with the same base line used for location of the 85 distant point, and the distance from the balloon to the ground point.

Since the position of the balloon is constantly shifting it is apparent that the correctional data, which will relate the ground 90 point to the distant point by interpolation into the data relating the distant point with the balloon, must be gathered practically instantaneously, at the ground point, when the data is received at the latter position 95 from the observation balloon.

By the instrument of this invention, I am enabled to gather both the angle of the balloon with any given base line, and the distance to the balloon, at one and the same 100 observation, thus enabling the ground observer to instantly relate by angle and distance, the distant point which was noted from the balloon. The means proposed herein to achieve the desired results consist 105 first, of a circular plate 10 which is graduated at its periphery into degrees, minutes and seconds, or other angular measure, and

which is mounted upon a tripod 11 through the medium of leveling screws 12 which are operable in the head 13 of the tripod. A plumb-bob 14 may be employed in connection with the tripod 11 in order to define the vertical axis of the graduated plate 10. The plate 10 is centrally formed with a downwardly directed socket sleeve 15, the extremity of which enlarges to form a hemispherical guide 16. This guide is adapted to be snugly received within the upturned open socket 17, centrally carried upon the cover plate 18 of the tripod head. Vertically adjustable within the socket sleeve 15 is an "elevation" rod 19 which is graduated in accordance with some suitable scale to denote height units, as is indicated by the numeral 20. This elevation rod is hollow and at its upper extremity carries the sight cap 21 which is essentially conoidal in form, terminating in a sight point 22 and being provided with a stem 23 whereby it may be removably established upon the upper extremity of the elevation rod 19.

The rod 19 is maintained at its adjusted elevation by means of an upright split-socket 24 which is provided at the terminus of its slot 25 with a pair of ears 26. These ears are adapted to be drawn tightly together through the medium of a thumb screw 27 to clamp the socket firmly upon the rod 19. The socket 24 is erected upon the sight arm 28 which is revoluble upon the plate 10 through the medium of a bearing portion 29. The bearing supporting the sight arm is centered on the plate by the rod 19 which passes therethrough.

The sight arm 28 is of the hollow square construction illustrated particularly in Fig. 5 and for the greater portion of its length, exterior to the plate 10, is provided with vertical registering slots 30. The sight rod is graduated with horizontal distance units corresponding with the graduations of the elevation rod, and has slidably thereon a peep-box 31, which is formed upon its upper surface with a sight notch 32 in registry with the slots 30. Double slots 33 are formed within the sight rod 28 immediately over the graduated periphery of the plate 10, the under slots of each pair of slots 33, terminating in a point 34 whereby the angles set off upon the plate 10 by rotational movement of the sight arm 28 may be read off by the user of the instrument.

In practice, the tripod of the device is set up with its plumb-bob defining a vertical axis for the plate 10 which intersects a known point Z on the ground, and the angle plate is then leveled up by means of the screws 12, and oriented, preferably in such a manner that the zero of the angular graduation placed upon the plate 10 and the ground point Z, both lie within a known base line such as the north and south line

35 of Fig. 6. An observer takes his stand by the instrument and a second observer is in telephonic communication with the captive balloon 36 from which the observational data to be corrected is acquired. It 70 is to be assumed that the recording instruments of the balloon are oriented along a line 37 which is parallel to the orient line of the ground instrument. If the distant object whose range is required is the battery A, the observer in the balloon sighting thereat discovers the angle which is denoted by the character a .

The angle b changes with the drift of the balloon and is one of the angles to be 80 discovered through the use of my instrument. This angle equals the angle d set off from the orient line 35 when the balloon is sighted through my instrument. Immediately upon receipt of the reading for 85 angle a , the ground observer is able to subtract the angle a from b to secure the total angle X. The balloon observer also telephones down the distance along his line of sight m projected on the ground. With 90 the knowledge of the length n' of the projected line of sight n connecting the ground point with the balloon, the ground observer is now able to calculate the triangle whose apexes are determined by the balloon, the ground point Z and the distant point A. With this range triangle determined, the distance along the line M and the angle Y which such line makes with the original reference line 35 may be read- 95 100ily figured, which is the range desired.

Reference to Fig. 7 will disclose the manner in which the instrument is used to ascertain the distance of the line of sight n , when projected along the line n' . At the 105 same time that the balloon observer furnishes the other data with reference to the range triangle, he adds the elevation of the balloon at that moment, which gives the distance y in this figure. The elevation rod 110 19 of the instrument is quickly set to the scale mark corresponding to the distance y and the observer at the instrument alines the sight of the peep-box 31 with the sight point 22 and with the basket of the balloon 115 36 so that by the theory of similar triangles the distance n' may be read off upon the scale of the arm 28.

It is to be noted that the simple act of sighting for the balloon along the line of 120 sight determined by the elevational arm 19 and the slidable peep-box 31 at once discovers the distance n' upon the sight arms 28 and the angle d upon the plate (O) thus enabling the instrument observer to 125 immediately interpolate these quantities into the observational data for the attainment of the correct angle and distance of the range M. Since the observer at the instrument is constantly following the shift- 130

ing balloon with the instrument, that is, maintaining the balloon in constant focus along the sight line *n*, the correctional data need only to be read off the plate 10 and 5 the arm 28 at any given moment for use in connection with the data gathered from the balloon in determination of successive range triangles.

What I claim is:

- 10 1. In a range finding instrument, a plate carrying angular graduations, an arm centered on the plate and carrying linear graduations, a second arm centered on said plate at right angles to the first arm for rotation 15 thereabout, and likewise provided with linear graduations, a sight point fixed upon the first said arm and a sight box slidable upon the second said arm.
2. In a range finding instrument, a plate 20 carrying angular graduations, an element on said plate and carrying linear graduations, a sight point carried by said element, a second element associated with said plate and adjustable with relation thereto and a sight 25 box adjustably mounted on said second element, said sight box being adapted to be placed in visual alinement with said sight point and another object.
3. In a range finding instrument, a plate 30 carrying angular graduations, an arm pivotally mounted at the center of said plate and carrying linear graduations, a sight box slidably carried by said arm, slots being formed in said arm through which said sight 35 box may be viewed and through which the graduations on said plate may be viewed, and an elevation rod provided with a sight point, said sight point being adapted to be placed in visual alinement with said sight 40 box and another object.
4. In a range finding instrument, a plate having angular graduations and provided 45 with a socket, an arm having a bearing upon said plate, a second arm adjustably mounted in said socket and at right angles to the first mentioned arm, to center the bearing of the latter upon said plate.
5. In a range finding instrument, a graduated plate, a graduated arm mounted for 50 rotation in a plane substantially parallel to the plane of said plate, a second graduated arm substantially at right angles to said plate, said arms being adjustable with relation to each other, a sight point carried by 55 said second arm, a sight box adjustable longitudinally on said first arm and provided with a peep hole whereby said sight box and said sight point may be brought in visual alinement with some other object.
- 60 6. In a range finding instrument, a graduated plate, a graduated arm mounted for rotation in a plane substantially parallel to

the plane of said plate, a second graduated arm substantially at right angles to said plate, said arms being adjustable with relation to each other, a sight point carried by one of said arms, a sight box adjustable longitudinally on the other of said arms and provided with a peep hole whereby said sight box and said sight point may be 70 brought in visual alinement with some other object.

7. In a range finding instrument, a plate carrying graduations, an arm disposed in approximately the same plane as said plate, 75 a second arm at approximately right angles to said first arm, the first and second arms being adjustable with relation to each other, and with relation to said plate, and a sight box adjustably mounted on said first arm, 80 all for the purpose described.

8. In a range finding instrument, a plate carrying graduations, an arm disposed in approximately the same plane as said plate and adjustable with relation thereto, a second arm disposed at approximately right angles to said first arm, said first and second arms being adjustable with relation to each other, and a sight box adjustably mounted on one of said arms, all for the 90 purpose described.

9. In a range finding instrument, a graduated plate, a horizontal arm mounted for movement in a plane substantially parallel to said plate and adjustable with relation 95 thereto, an arm perpendicular to said horizontal arm, said horizontal and perpendicular arms being adjustable with relation to each other, a sight point on said perpendicular arm, a sight box adjustably carried by said horizontal arm for alinement with said sight point and some other object, and means whereby the perpendicularity of said perpendicular arm may be assured.

10. In a range finding instrument, a graduated plate, a graduated arm perpendicular thereto, a graduated horizontal arm mounted for rotation about said perpendicular arm as an axis and in a plane substantially parallel to said plate, said perpendicular and horizontal arms being adjustable with relation to each other, a sight point on said perpendicular arm and a sight box adjustably carried by said horizontal arm for alinement with said sight point and some other 110 object.

In testimony whereof, I have signed my name in the presence of two subscribing witnesses.

RALPH H. UPSON.
